LOCK

Morgan S. Elmer, Central Valley, N. Y.

Application September 11, 1947, Serial No. 773,471

9 Claims. (Cl. 292—130)

1

This invention relates, in general, to improvements in locks for sliding and swinging doors and similar closures and deals, more particularly, with an improved bolt type of lock comprising a latch having a lever operating means for easily and quickly actuating the latch and drawing the door or other closure tightly shut together with means providing a positive lock of the latch in tightly drawn position but capable of ready release for quick and expeditious opening of the door or other closure.

A primary object of the invention is to provide an improved, highly simplified lock of this character in a compact, unitary assembly of parts comprising a sliding and/or swinging bolt or latch member which is actuated by an operating lever with ease and facility to draw up the latch for securing the door or other closure in tightly shut position.

A further object of the invention is to provide such a lock construction having a positive lock for the latch or bolt in tightened, drawn-up position comprising a pawl and ratchet means associated with the operating lever.

Another object of the invention is to provide a lock of the kind described having means which may be employed for sealing the lock by a padlock or other sealing device.

A further object of the invention is to provide an improved lock having all the foregoing features of construction, and which comprises a strong, durable and fool-proof assembly which is relatively simple in construction and therefore, may be manufactured at comparatively low cost.

Further objects and advantages of the invention, and other new and useful features in the construction, arrangement and general combination of parts of the invention will be readily apparent as the following description proceeds with reference to the accompanying drawings, for purposes of illustration but not of limitation, in which like reference characters designate like parts throughout, and in which:

Fig. 1 is a side elevational view of the improved lock construction in accordance with the invention, with the associated door or other closure represented in section;

Fig. 2 is a sectional view of Fig. 1 as seen along line 2—2, looking in the direction of the arrows;

Fig. 3 is a horizontal sectional view of Fig. 1 showing the improved lock construction in top plan, with the door frame and associated door or other closure represented in section; and,

Fig. 4 is a sectional view of Fig. 1 taken along line 4—4, looking in the direction of the arrows,

and showing the attachment of the auxiliary eye lug for locking the operating lever or for sealing the lock when desired.

The improved lock of the invention is one of general utility and has a wide range and variety of applications and uses as a lock for either sliding or swinging doors, particularly in heavy duty installations such as, for example, a sliding door of a refrigerator car, or, a swinging door of a garage or barn or the like, by way of illustration.

Referring now, more particularly, to the drawings, the improved lock is illustrated in a typical mounting which may be provided in any structure comprising a frame 1, having a suitable stop or seat for the free end of a sliding or swinging door 3, or other closure. The door 3 is provided in any suitable manner with a staple 5, or the like, which is adapted to be hooked or otherwise engaged by the latch member of the lock mechanism in drawing the door tightly shut and securing the door in such tightly shut position. In the present example, the staple 5 is shown in Fig. 1 as attached to the door 3 in a flush mounting provided by a suitable cutout 4 in the door and preferably in flush relation thereto so that the staple does not constitute a dangerous projection nor become an obstacle in the path of a sliding door. The staple is shown as one which is riveted at its ends to a flange 6 that is suitably fastened at the outer face of the door 3, as by screws 7, with the body of said staple 5 extending through the cutout 4 to the inner face of the door.

The lock mechanism comprises a simplified, unitary assembly of parts on a base plate 10 which is attached to the frame 1 in any suitable manner as by screws 11. A series of ratchet teeth 13 are provided by notches along an upper edge of said base plate 10 or, in an equivalent arrangement by a ratchet strip united to said base plate in the same general relation.

An operating lever 15, having a handle 16 is pivotally mounted on the base plate 10 as by a headed pin 17 peened in a countersunk hole in said base plate. A pivoted pawl 20 is carried by the operating lever 15 on the inner side or face thereof with the extremity or tongue of said pawl in position for selective engagement with said ratchet teeth 13 on the base plate. The pawl 20 is pivotally mounted to the operating lever 15 preferably by a rotary pintle having a wing head 22 which may be easily manipulated by the fingers of the user to turn the pawl 20 into or out of engagement with the ratchet teeth 13 in the operation of the lock, as presently to be described.

If desired, the pawl 20 may be provided with a biasing spring such as a light coil spring or a leaf spring urging the pawl to engaging position with the ratchet teeth 13 but capable of yielding readily under turning force on the wing head 22 to permit said pawl to be disengaged from the ratchet teeth when the lock is to be released. The pawl 20 is thus pivotally carried on the inner side or face of the pivoted operating lever 15, and on the opposite outer side or face of said lever, a bolt or latch 30 is pivotally mounted by a pin 31 in a manner whereby said latch 30 is adapted for a combined swinging and sliding motion in the general plane thereof.

The latch 30 is provided with a suitable weight 33 on its rearward free end and a pronounced hook 35 on its forward end adapted to engage and connect with the staple 5 as shown in Fig. 1. The motion of the latch is controlled and guided by a slotted guide element 36 having a slot through which the latch 25 reciprocates in the swinging and sliding motion thereof, as aforesaid. The slotted guide 36 may be formed from an integral outwardly bent projection on the base plate 10 or by a similar element welded to the base plate in an equivalent relation. In any event, the ends of the slot in said guide element 36 define an upper guide shoulder 37 and a lower guide shoulder 38 disposed at the opposite side edges of said latch 30.

The latch 30 is provided on its lower edge in the manner of a cam surface 34 adapted for sliding engagement with the lower guide shoulder 38 of the guide element 36. The said cam surface 34 is so designed as to effect a predetermined motion for release of the latch from secured position in a manner whereby the hook 35 is forced upwardly to clear the staple 5 and is thereby properly positioned for separation from said staple, whereupon the latch is drawn rearwardly by the operating lever 15 to fully retracted position in the operation of the lock, as presently to be described. The combined swinging and sliding reciprocatory motion of the latch 30 otherwise is controlled and guided along the lower edge of the latch by the sliding contact of the cam edge 34 with the lower guide shoulder 38 defined by the slot in the guide element 36.

Along similar lines, when the hook 35 is disengaged from the staple in releasing the lock, the latch is tilted by the weighted end 33 thereof, whereupon the latch is guided in its rearward movement by the sliding engagement of the upper edge of the latch with the upper guide shoulder 37 of said guide. In the fully retracted position of the latch, as represented in dotted lines in Fig. 1, the head of the hook 35, is adapted to rest against said upper guide shoulder 37. The sidewalls of said slot in the guide element 36 are adapted to engage the side faces of the latch in its reciprocatory motion to guide the same and otherwise prevent any undue lateral movement thereof out of its normal path for proper engagement of the hook 35 with the staple 5.

The lock assembly described is a complete and operative mechanism in itself, and when desired, may be readily provided with means for sealing the same by a padlock or other sealing means. To this end, the operating lever is provided with an outwardly projecting eye lug 41 which may be either an integral formation on said lever or a separate element united thereto, as by welding, for example. A cooperating eye lug 42, Fig. 4, is provided with a projecting stud 43 which is removably insertable in any of a series of holes 44

in the base plate 10 in a manner to position said eye lug 42 in alignment with the eye lug 41 carried by the operating lever. The eye lug 42 otherwise defines a stop preventing any forward movement of the operating lever 15 and the associated latch 30 in the direction toward removal of the hook 35 from connected engagement with the staple 5. In this relation, the eye lug 42 adds to the locking action on the operating lever 15 provided by the pawl 20 in engagement with the ratchet teeth 13, as aforesaid. In a further relation, the lug 42 as selectively applied to any of the series of holes 44, in the base plate 10, Fig. 1, may be used as a stop lug for holding the operating lever 15 in the locked position of the latch 30 in place of the pawl 20 and the associated ratchet teeth 13. In any case, in the locked position of the latch, the eye lug 42 is aligned with the eye lug 41 on the operating lever 15 in a manner whereby a padlock or other sealing device may be passed through the aligned openings in said eye lugs 41, 42, to seal the lock. The removable auxiliary eye lug 42, Fig. 4, is a separate device as described, and preferably is attached to the base plate 10 or adjacent structure by a chain or cord 46 secured to an eyelet 47 thereon and to the base plate 10 or adjacent structure in any suitable way as by a similar eyelet 48. The eye lug 42 normally is removed from any of the holes 44 in the base plate 10, Fig. 1, so that the operating lever 15 is free to pivot forwardly and rearwardly as indicated by the arrows in Fig. 1 in the ordinary usage of the lock. However, when it is desired to seal the lock with the various parts thereof in the position represented in the full lines in Fig. 1, the said auxiliary eye lug 42 is attached in the selected hole 44 and a padlock or equivalent applied to the aligned eye lugs 41, 42, to seal the lock, as aforesaid.

In the operation and use of the lock, it will be understood from the foregoing that with the auxiliary eye lug 42 removed from the position shown in Fig. 1, the operating lever 15, latch 30 and pawl 20 carried thereby are disposed in retracted, unlocked position substantially as represented in broken lines. To secure the lock, the handle 16 is grasped to move forwardly as far as possible the lever 15 and the pivotally attached latch 30 to the position in which the hook 35 on said latch is in overlying relation to the staple 5 and may be readily hooked onto said staple. The latch 30, accordingly, is pushed downwardly to connect said hook 35 with the staple 5, and is then tightened, or drawn-up in such connected engagement with the staple 5 by a reverse movement of the latch 30 which is effected by a rearward pull on the operating lever 15. When the latch 30 has been sufficiently drawn up to tighten the hook 35 suitably and thereby tightly shut the door 3, the operating lever is positively locked against loosening or release of the hook from such position by engagement of the pawl 20 with the effective ratchet tooth on the ratchet 13. This is accomplished by turning the associated wing head 22 or, automatically, by a suitable spring for urging the pawl into engagement with the ratchet, as aforesaid.

An equivalent locking of the operating lever 15 may be effected by the eye lug 42 in lieu of or supplementary to the pawl and ratchet elements 20, 13, respectively. In this regard, the stud 43 of said eye lug 42 is inserted into the effective hole 44 in the base plate 10 depending on the aforesaid drawn-up tightening position of the operating lever 15. The eye lug 42, accordingly, is in

abutting engagement with the eye lug 41 on the lever to prevent movement of said lever in the forward direction toward release or loosening of the hook 35 from the staple 5. The openings in the eye lugs 41, 42, are aligned in any such position, whereupon a padlock or other sealing device may be applied to the aligned eye lugs to seal the lock.

Release of the lock is easily and quickly effected simply by removing the eye lug 42 and disengaging the pawl 20 from the ratchet 13, whereupon the lever 15 is moved forwardly as necessary for the hook 35 to disengage and clear the staple 5. This is facilitated in such forward movement of the latch 30 by the engagement of the cam surface 34 on said latch with the lower guide shoulder 38 which quickly initiates the lifting of the hook 35 from connected relation with said staple 5. The weight 33 on the rearward end of the latch is then effective to complete the lifting of the hook from the staple and otherwise clear the hook from said staple, whereupon the operating lever 15 is pulled rearwardly to move said lever and the associated latch to retracted position substantially as shown by broken lines in Fig. 1. The door 3 is then free to slide or swing open and when subsequently shut and it is desired to lock and/or seal the same, it is easily and quickly secured by the improved lock of the present invention in a repetition of the foregoing described procedure.

While the invention has been described in detail with a specific example, such example is intended as an illustration only, since it will be apparent to those skilled in the art that other modifications in the construction, arrangement and general combination of parts may be devised without departing from the spirit and scope of the invention. The present embodiment is therefore to be considered in all respects as illustrative and not restrictive, the scope of the invention being indicated by the appended claims rather than by the foregoing description, with all changes falling within the scope, meaning, and range of equivalency of the claims intended to be embraced therein.

What is claimed and desired to be secured by United States Letters Patent is:

1. In a lock, a locking mechanism comprising a base plate, an operating lever pivotally attached to said plate, a latch having a cam guiding surface, said latch being pivotally mounted on said lever and adapted to be moved to securing and released positions by said lever, means for holding said lever in various positions in which said latch is secured to prevent release of said latch when in securing position, and a guide member on said plate having a guide slot receiving said latch and defining a guide shoulder on which said cam guiding surface on the latch is adapted to ride in the releasing of a latch.

2. In a lock, a locking mechanism comprising a base plate having a ratchet element, an operating lever pivotally attached to said plate, a latch having a cam guiding surface, said latch being pivotally mounted on said lever and adapted to be moved to securing and released positions by said lever, a guide member on said plate having a guide slot receiving said latch and defining a guide shoulder on which said cam guiding surface on the latch is adapted to ride in the releasing of the latch, and means for holding said lever in various positions in which said latch is secured to prevent release of said latch when in securing position, said means comprising a pawl

on the operating lever engageable with said ratchet element on the base plate.

3. In a lock, a locking mechanism comprising a base plate having a ratchet element, an operating lever pivotally attached to said base plate, a latch having a downwardly and rearwardly directed hook on one end, a weight on the other end and a cam guiding surface, said latch being pivotally mounted on said lever and adapted to be moved to securing and released positions by said lever, a guide member on said plate having a guide slot receiving said latch and defining a guide shoulder on which said cam guiding surface on the latch is adapted to ride in the releasing of said hook on the latch, and means for holding said lever in various positions in which said latch is secured to prevent release of said latch when in securing position, said means comprising a pawl on the operating lever engageable with said ratchet element on the base plate.

4. In a lock, a locking mechanism comprising a base plate, an operating lever having a pivot to said base plate and extending generally vertically in said lock, a latch pivotally mounted on said lever above its pivot to the base plate extending generally horizontally in said lock, said latch having a downwardly and rearwardly directed hook adapted to engage a keeper in locking position and having a weight on one end for automatically tilting said latch out of locking position when released by said lever, and means for holding said lever against movement when said latch is secured.

5. In a lock, a locking mechanism comprising a base plate, an operating lever having a pivot to said base plate and extending generally vertically in said lock, a latch pivotally mounted on said lever above its pivot to the base plate extending generally horizontally in said lock, said latch having a downwardly and rearwardly directed hook adapted to engage a keeper in locking position and having a weight on one end for automatically tilting said latch out of locking position when released by said lever, and means for holding the lever in various positions in which said latch is secured.

6. In a lock, a locking mechanism comprising a base plate having a ratchet element, an operating lever having a pivot to said base plate and extending generally vertically in said lock, a latch pivotally mounted on said lever above its pivot to the base plate extending generally horizontally in said lock, said latch having a downwardly and rearwardly directed hook adapted to engage a keeper in locking position and having a weight on one end for automatically tilting said latch out of locking position when released by said lever, and means for holding the lever in various positions in which said latch is secured comprising a pawl carried by said lever and engageable with said ratchet element on the base plate.

7. In a lock, a locking mechanism comprising a base plate, an operating lever having a pivot to said base plate and extending generally vertically in said lock, a latch pivotally mounted on said lever above its pivot to the base plate and extending generally horizontally in said lock, said latch having on one end a cam guiding surface and a downwardly and rearwardly directed hook adapted to engage a keeper in securing position, and a weight on the other end for automatically tilting said latch out of securing position when released by said lever, a guide member on said plate having a guide slot receiving said latch and defining a guide shoulder on which said cam

guiding surface on the latch is adapted to ride in the releasing of said latch, and means for holding said lever against movement when said latch is secured.

8. In a lock, a locking mechanism comprising a base plate, an operating lever having a pivot to said base plate and extending generally vertically in said lock, a latch pivotally mounted on said lever above its pivot to the base plate and extending generally horizontally in said lock, said latch having on one end a cam guiding surface and a downwardly and rearwardly directed hook adapted to engage a keeper in securing position, and a weight on the other end for automatically tilting said latch out of securing position when released by said lever, a guide member on said plate having a guide slot receiving said latch and defining a guide shoulder on which said cam guiding surface on the latch is adapted to ride in the releasing of said latch, and means for holding said lever in various positions in which said latch is secured.

9. In a lock, a locking mechanism comprising a base plate having a ratchet element, an operating lever having a pivot to said base plate and extending generally vertically in said lock, a latch pivotally mounted on said lever above its pivot to the base plate and extending generally horizontally in said lock, said latch having on one end a cam guiding surface and a downwardly and rearwardly directed hook adapted to engage a

5 keeper in securing position, and a weight on the other end for automatically tilting said latch out of secured position when released by said lever, a guide member on said plate having a guide slot receiving said latch and defining a guide shoulder on which said cam guiding surface on the latch is adapted to ride in the releasing of said latch, and means for holding said lever in various positions in which said latch is secured comprising a pawl on the operating lever engageable with said ratchet element on the base plate.
